ROSE MERKIN, OF BOSTON, MASSACHUSETTS.

CORSET.

1,012,406.

Specification of Letters Patent. Patented Dec. 19, 1911.

Application filed March 8, 1910. Serial No. 548,142.

To all whom it may concern:

Be it known that I, ROSE MERKIN, a citizen of the United States, and resident of Boston, in the county of Suffolk and State of Massachusetts, have invented new and useful Improvements in Corsets, of which the following is a specification.

This invention relates to corsets, and its objects are to provide a novel and improved construction of corset wherein the stays are removable, to provide novel and improved abdominal straps, and to provide in a single garment a combined corset and bust supporter of novel and improved construction. 10 These and other features of the invention will be hereinafter more specifically pointed out.

In the accompanying drawings which illustrate the invention, — Figure 1 is a front perspective view of a corset containing my invention; Fig. 2 is a similar view of the lower part of the garment showing the abdominal straps unfastened and open; Fig. 3 is a detail sectional view, enlarged, 20 on line 3—3 of Fig. 1; Fig. 4 is a detail front view of the lower part of one of the front edges of the corset body; Fig. 5 is a detail front view of a part of the corset body near the upper edge showing the construction of the upper part of one of the stay sheaths; Fig. 6 is a cross section on line 6—6 of Fig. 5; Fig. 7 is a longitudinal section on line 7—7 of Fig. 5; Fig. 8 is a front view of the upper end of one of the 30 removable stays; Fig. 9 is a similar view to that shown in Fig. 5, but showing a modification thereof; Fig. 10 is a vertical section on line 10—10 of Fig. 9; Fig. 11 is a plan view of the piece used to form a reinforced pocket as hereinafter described; Fig. 40 12 is a front view, enlarged, of the upper front corners of the body halves of the corset; and Fig. 13 is a cross section on line 13—13 of Fig. 12.

Referring to the drawings, A represents the body of the corset consisting of two body halves of suitable fabric laced together at the back as usual. In order that all the steels or stays and the metal fasteners may 50 be readily removed, for the purpose of laundering the corset, or to replace broken stays, and that they may as readily be inserted again in the corset, a number of stay sheaths are formed by stitching a strip of

fabric a at its edges, to the fabric forming the body of the corset, by the lines of stitches a'. Thus a tubular or hollow channel or sheath is provided closed at its bottom by the line of stitches a'', and at its top by a top line of stitches a''' or by a reinforcement hereinafter described. In the front side of each sheath so formed is a button-hole, slot or aperture, a'', near, but a short distance below, the top of the sheath, so that a pocket is left above each aperture a''' to receive and hold the upper end of a removable stay. In order to prevent danger of the upper ends of the stays breaking through, I line each pocket at the top of the sheath, with a reinforcement, consisting of a strip of suitable fabric a''' one end of which is sewed to the upper edge of the aperture a'', whence the reinforcement extends upward along the front side of the sheath far enough to form a pocket lining 75 of sufficient depth; thence it is folded backward on itself at a'', and thence it extends downward along the back side of the sheath and terminates at a point a''' considerably below the aperture a'', so that the edge a''' of the reinforcement cannot possibly catch the end of the stay. The sides of the reinforcement a''' are sewed into the sheath by the same line of stitches a''' which close the sides of the sheath. In the form shown in 85 Figs. 5 and 7 the front edge of the reinforcement terminates at the edge of the aperture a'' and is secured thereto by the same button-hole stitches which finish the edge of the aperture. In the modification 90 shown in Figs. 9 and 10 the front end of the reinforcement is extended to form a tab a''' which overlies and closes the aperture a''.

B, B, represent stays, made of steel or other suitable material, adapted to slip 95 through the apertures a''. The stays B, B, are of a length not exceeding the length of the sheath from the bottom thereof to said apertures a''. Thus, to insert the stays, they may be slipped downward through the apertures a'' until the upper ends pass through said apertures. Thereafter they may be pushed upward until the top ends b of the stays are lodged within the reinforced pockets at the tops of the sheaths. The stays 105 will naturally remain in this position when the corset is being worn, since their tendency is to work upward. As additional se-

curity however, a separable snap fastener may be used, the stud member b' being secured to the stay B, and the socket member b'' being secured to the inner side of the 5 pocket lining formed by the strip a'' . About midway of the length of the sheaths a second slot or aperture a'' is formed in the face of the sheath, through which a stay may be drawn out if it becomes broken. 10 Stays are most frequently broken at about the waist line, and the broken end is usually ragged and bent so that it would be difficult to draw it through the whole length of the sheath to the hole a'' . The middle 15 hole a'' is then used.

The construction of the stays and sheaths thus far described is applicable to the sides and back of the corset.

Referring now to the front stays and the 20 sheaths therefor, one of the front meeting edges of the corset body, the left hand edge as viewed in the drawings, is folded backward on itself and stitched to the body fabric by a line of stitches a' to form a wide 25 channel or sheath c (see particularly Figs. 3, 12 and 13). A slot or aperture c' is made in the face of the sheath c , near, but a short distance below the top of the sheath. At the extreme edge of said front sheath are 30 a number of slots or apertures c'' for the fasteners of the front stay. A plurality of stud holes c'' are also provided through the face of the sheath near the edges thereof. The removable front stay contained within 35 the sheath c consists of the body part D having secured thereto at intervals the fastening loops d . The sheath c is made at least as wide as the combined width of the stay D and the fastening loops d , as is also 40 the aperture c' , so that the front stay with its fasteners may be slipped into the front sheath through aperture c' until the loops d come opposite the edge slots c'' . The front stay is then moved to the outer side 45 of the sheath, the loops d projecting through the slots c'' , and studs d' , mounted on stay D, are buttoned through the stud holes c'' , to hold the stay in position. When the stay is to be removed the studs d' are 50 withdrawn from the stud holes, and the stay D moved across the sheath until the loops d are drawn into the sheath, whereupon the stay may be slipped lengthwise outward through slot c' . The opposed 55 front edge of the corset body is similarly provided with an edge sheath e made by stitching down a folded portion of the material at a' , and is provided with a similar aperture e' near the top, and similar stud holes e'' . The stay E is made with studs e'' for engaging the stud holes e'' , and studs e'' for engaging the fastener loops d of the opposite stay. The fastening studs e'' pass 60 through eyelets e'' in the face of the sheath e . 65 Secured to either side of the lower front

portion of the corset body, at points removed from the meeting edges, are elastic straps F and F' which may be adjustably fastened together by a buckle f . Said elastic straps are secured to the body only at 70 their remote ends, and are free and disconnected both at their meeting ends and throughout practically their whole length, thus affording great latitude of adjustment. A hook or other suitable holder f' is secured to the body of the corset to hold the straps F and F' down in inclined position when the straps are fastened together. Said straps are adapted to support and compress the abdomen.

G, G, represent a pair of diagonal flaps secured to the lower front part of the corset body at the outer sides of the elastic straps F, F'. Said flaps overlie and cover said elastic straps, and are made with elongated 80 downwardly extending ends g adapted to carry hose supporters. Said flaps G cross each other as shown in Fig. 1 and when the hose supporters are attached to the ends g , with the right hand hose supporter carried by the left hand flap and vice versa, the tension exerted thereby tends not only to draw the flaps downward, but also across each other toward the center of the corset. Thus the flattening and compressing function performed by the flaps will be more perfect than with devices heretofore designated. Said flaps are fastened together by 85 snap fastener members g' , g'' , secured to the area where the flaps cross each other; and each flap is also fastened directly to the opposite body section of the corset by the snap fasteners g^2 and g^3 respectively.

Above the stiffened or reinforced body part of the corset, each body section is provided with an unstiffened, flexible tab H extending upward from the front edge of the body section. The opposed edges h of the two tabs are spaced apart, as shown, when the stiffened body sections of the corset are fastened, so that a wide range of adjustment is permitted when the lacings L are laced through the eyelets h' . A tie or ribbon R may be employed if desired at the upper parts of each tab H. Each tab 100 H is separably and adjustably connected with the upper edge of the rear of the corset body, by a strap h'' which passes over the shoulder. Said straps are adjustable 105 in length by buckles h^3 . Thus there is combined in one garment a corset reinforced by stays, and an unstiffened, adjustable, bust supporter, making it possible to dispense with the necessity of wearing an additional 110 waist or bust supporter over the corset. Furthermore, the bust supporter and the straps tend to hold the upper edges of the 115 stiffened body, at both front and back, close to the body, thus preventing the ends of the stays from springing outward, especi- 120 125 130

ally when the body of the wearer is bent, and showing through even the outer garments, as is frequently the case with ordinary corsets. This tendency of the stiffened part of the body to spring outward and show through the waist is particularly conspicuous at the upper ends of the front stays of a corset, but is wholly avoided in my corset by the lacings L which lead from the upper front corners of the stiffened parts of the corset adjacent to the upper ends of the front stays D, E, and draw the ends of said stays inward toward the body of the wearer when the lacings are laced through the eyelets h' of the bust supporter portions H, thus insuring a well-fitting, curved line, instead of an abrupt angle, at the point where the front stays terminate. It will also be observed that the unstiffened bust supporter portions, H, and the shoulder straps h², are made integral, each with its own body section, thus rendering the garment free from the disadvantages of seams, and much more durable than it would be if said parts were made of separate pieces of material and stitched to the body sections.

I claim:

1. In a corset, a number of stay sheaths closed at both ends, each provided with an aperture located in the side of the sheath near, but a short distance below, the top of the sheath, forming a pocket for the upper end of the stay above the aperture, a reinforcement lining said pocket extending from the upper edge of said aperture upward along the front side of the sheath and thence downward on the opposite side of said sheath to a point below said aperture, and a removable stay in each such sheath adapted to pass through said aperture, said stay being of a length not exceeding the length of the sheath from the bottom thereof to said aperture.
2. In a corset, a stay sheath closed at both ends, formed by stitching two or more plies of material together, said sheath provided with an aperture or slot located in the side of the sheath near, but a short distance below, the top of the sheath, forming a pocket for the upper end of the stay above the aperture, a reinforcement lining said pocket, consisting of a piece of suitable material the sides of which are stitched into the sheath by the same stitches which close the sides of the sheath, one end of which is secured to the upper edge of the aperture by the same stitches which are used to finish said edge of the aperture, and the other end of which extends downward to a point below the aperture, and a removable stay in said sheath.
3. In a corset, a number of stay sheaths closed at both ends, each provided with an aperture located in the side of the sheath near, but a short distance below, the top of

the sheath, forming a pocket for the upper end of the stay above the aperture, a reinforcement lining said pocket extending from the upper edge of said aperture upward along the front side of the sheath and thence 70 downward on the opposite side of said sheath to a point below said aperture, a removable stay in each such sheath adapted to pass through said aperture, each stay being of a length not exceeding the length of its sheath 75 from the bottom thereof to said aperture, and a flap extending from the upper edge of the aperture and covering the same, said flap consisting of an extension of said reinforcement.

4. In a corset, a front stay sheath at one of the front edges of the corset, said sheath having a number of edge apertures through its extreme edge, a face aperture through its side at or near the top, and stud holes, and 80 a removable front stay therein provided with fastening members projecting laterally through the edge apertures, and studs adapted to engage said stud holes to hold the stay in place, the width of said sheath and the 85 width of said face aperture each being at least as great as the combined width of the front stay and its projecting fastening members.

5. In a corset, in combination with the 95 body section, a pair of angular shaped flaps G each comprising a diagonal portion and downwardly depending hose supporter portion, said flaps secured one to each side of the lower front portion of the corset body, 100 at a point removed from the meeting edges of the corset body, said flaps adapted to cross each other and each to overlie the opposite body section of the corset, means separably to attach the underlying flap to the 105 opposite body section, and means separably to attach the overlying flap to its opposite body section at a point beyond the underlying section.

6. A combined corset and bust supporter, 110 comprising two body sections each having its lower part reinforced and stiffened by stays, and an upwardly extending unstiffened bust supporter part formed integrally of the same piece of material with the lower part, 115 the opposed edges of the bust supporter parts of the two sections being spaced apart and provided with eyelets, lacings leading from the upper front corners of the stiffened parts of the corset sections adjacent to the upper ends of the front stays adapted to engage with said eyelets both to draw said bust supporter parts together and to hold the upper ends of said stays inward, and a strap connecting the top of each bust supporter part 120 with the upper edge of the rear of the body section.

7. A combined corset and bust supporter, 125 comprising two body sections each having its lower part reinforced and stiffened by 130

stays, and an upwardly extending unstiffened bust supporter part formed integrally of the same piece of material with the lower part, the opposed edges of the bust supporter parts of the two sections being spaced apart and provided with eyelets, lacings adjustably to connect said bust supporter parts, and a strap connecting the top of each bust sup-

porter part with the upper edge of the rear of the body section.

Signed at Boston, Massachusetts, this ¹⁰
fourth day of March, 1910.

ROSE MERKIN.
